US00D723561S

(12) **United States Design Patent**
Buel et al.

(10) **Patent No.:** **US D723,561 S**
(45) **Date of Patent:** **** Mar. 3, 2015**

- (54) **THREE-DIMENSIONAL SCANNER**
- (71) Applicant: **MakerBot Industries, LLC**, Brooklyn, NY (US)
- (72) Inventors: **William B. Buel**, New York, NY (US); **Vishnu Ananatha**, Queens, NY (US); **Taylor S. Goodman**, Chappaqua, NY (US)
- (73) Assignee: **MakerBot Industries, LLC**, Brooklyn, NY (US)
- (**) Term: **14 Years**
- (21) Appl. No.: **29/462,058**
- (22) Filed: **Jul. 30, 2013**
- (51) LOC (10) Cl. **14-02**
- (52) U.S. Cl. **USPC D14/420**
- (58) **Field of Classification Search**
USPC D14/420-423, 385; 433/222.1, 223, 433/213-215, 73, 24, 29, 37, 202.1; 700/98, 97, 118, 161, 163, 182; 264/16, 17, 19, 219, 225; 374/1; 707/104.1; 249/54; 600/590; D20/1-9; 194/205, 206, 244, 321, 345, 346, 350; D18/3.3, 4.4, 12, 49; D99/28, 43; 235/381

(57) **CLAIM**

We claim the ornamental design for a three-dimensional scanner, as shown and described.

DESCRIPTION

FIG. 1 is a front perspective view of a three-dimensional scanner;
FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

Broken lines and entirely unshaded portions contained within broken line are not claimed.

1 Claim, 4 Drawing Sheets
